FIG. 1

FIG. 2

FIG. 3

Des. 211,930

PAGE 2

FIGURE 1 is a front elevational view of a combined bottle and cover therefor embodying my new design, the rear being the same in appearance;

FIGURE 2 is a side elevational view, the opposite side being the same in appearance;

FIGURE 3 is a top plan view;

FIGURE 4 is a perspective view;

FIGURE 5 is another front elevational view with the cover removed from the top and placed on the bottom structure; and

FIGURE 6 is a side elevational view of the design as seen in FIGURE 5.

The dominant features of my design reside in the portion shown in full lines.

I claim:

The ornamental design for a combined bottle and cover therefor, as shown and described.
